TELEVISION CABINET

John J. Houlihan, Huntington, W. Va.

Application November 9, 1953, Serial No. 27,499

Term of patent 14 years

(Cl. D56—4)

To all whom it may concern:

Be it known that I, John J. Houlihan, a citizen of the United States, residing at Huntington, in the county of Cabell, State of West Virginia, have invented a new, original, design for a Television Cabinet, of which the following is a specification, reference being made to the accompanying drawing, forming part thereof, and in which:

Fig. 1 is a side elevational view of a television cabinet showing my new design;

Fig. 2 is a front elevation thereof; and,
Fig. 3 is a top plan view thereof.

The dominant features of my design reside in the portions shown in full lines.

I claim:

The ornamental design for a television cabinet, substantially as shown and described.
